(57) **CLAIM**

I claim the ornamental design for a rifle bullet, as shown and described.

DESCRIPTION

FIG. 1 is a perspective view of the rifle bullet.

FIG. 2 is a perspective view of the rifle bullet.

FIG. 3 is a side view of the rifle bullet.

FIG. 4 is a rear view of the rifle bullet.

FIG. 5 is a front view of the rifle bullet; and,

FIG. 6 is a longitudinal cross section of the rifle bullet.

The broken lines showing of a shell casing in FIGS. 1 and 2 illustrates environment which forms not part of the claimed design.
